(57) **CLAIM**

The ornamental design for an orthopedic surgical instrument as shown.

DESCRIPTION

FIG. 1 is a front perspective view of an orthopedic surgical instrument.

FIG. 2 is a rear perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the orthopedic surgical instrument that form no part of the claimed design.
